UNITED STATES PATENT OFFICE.

ROBERT J. BELL, OF HARVEY, ILLINOIS.

CLOTHES-HANGER BRACKET.

1,333,600.

Specification of Letters Patent. Patented Mar. 16, 1920.

Application filed November 12, 1919. Serial No. 337,440.

To all whom it may concern:

Be it known that I, ROBERT J. BELL, a citizen of the United States, residing at Harvey, in the county of Cook and State of Illinois, 5 have invented certain new and useful Improvements in Clothes-Hanger Brackets, of which the following is a specification, reference being had to the accompanying drawings.

10 This invention relates to clothes hanger brackets and has for its object to provide a device of this character including means for supporting separate articles of clothing and means for supporting a number of articles 15 of clothing at the same time.

Another object is to provide a single supporting member including a plurality of clothes supporting members one of which is capable of supporting a number of portable clothes hangers and the clothes thereon.

Another object is to provide a device of this character including a plurality of clothes supporting members, each member being arranged in close proximity to each 25 other without causing interference with the use of the adjacent member.

A still further object is to provide a device of this character the supporting plate and clothes supporting member of which can 30 each be manufactured from a single length of material.

With these and other objects in view the invention consists in the improved construction to be hereinafter more particularly described, fully claimed and illustrated in the 35 accompanying drawings, in which:

Figure 1 is a perspective view of a clothes hanger bracket constructed in accordance with my invention.

40 Fig. 2 is a modified form of supporting plate for the bracket.

Referring to Fig. 1 of the drawings 5 indicates a supporting plate having openings 6 through which means are passed for securing the plate to the desired support. A plurality of lugs 7 are struck from the plate and are curled upon themselves to provide aligned sockets 8 adapted to support the clothes supporting member 9.

50 The clothes supporting member 9 is movably connected to the plate by the sockets 8 so as to permit the same to be moved to one side when not in use. This member consists of a single length of material bent ad-

jacent its intermediate portions as at 10 to 55 provide arms 11 and 12 which extend in parallel relation to each other. The arm 11 is longer than the arm 12 and includes a plurality of kerfs 13 adapted to receive the hooks of portable clothes hangers to hold a 60 plurality of these devices in spaced relation to each other.

The end portion of the arm 11 is bent angularly as at 14 to provide a pintle and then upwardly and outwardly as at 15 and 65 then vertically as at 16, the extremity of the arm being curled to provide a hat support 17. By the novel construction of the end, the hat is supported in such a manner that it does not interfere with the supporting arms 70 11 and 12. The end portion of the arm 12 is bent angularly as at 18 in the opposite direction to the portion 14 to provide a pintle and has its end 19 curved toward the arm 12 to provide a clothes supporting hook. 75 The angularly bent portions 14 and 18 are pivotally connected to the plate by means of the sockets 8.

By this novel construction, the intermediate portion formed by the arms 11 and 12 80 is substantially supported from above and below in view of the novel arrangement of the lugs 7, the arm 12 serving to reinforce the arm 11 when pressure is applied thereto. In addition to this the ends of the arm 11 85 and 12 are extended to provide suitable supports, and in view of their position prevent disengagement of the portions 14 from the plate 5. The outer extremity of the member formed by the arms 11 and 12 is 90 bent to provide a projection 20 which prevents disengagement of the portable clothes hangers.

In Fig. 2 an additional securing method for the plate 5 is shown and consists of extending the upper end of the plate rearwardly in angular relation thereto as at 21, the end of the plate being extended downwardly in parallel relation to the body of the plate to provide a suitable hook capable 95 of being readily attached to a narrow support and at the same time efficiently support the clothes supporting member.

From the foregoing it will be readily seen that this invention provides a clothes 105 hanger bracket consisting of two members, namely the plate and the clothes supporting member, the latter being bent to provide

a plurality of clothes supporting members and to permit a portion of said member to be movably connected to the plate to efficiently support the clothes supporting member.

5 The invention having been set forth, what is claimed as new and useful is:—

1. As a new article of manufacture, a base member having opposed fingers struck therefrom, one end of each finger being integral 10 with the base, and a supporting member, consisting of a single length of material having one portion extended back upon the other portion to provide clothes supporting arms, each arm reinforcing the other, the 15 end portions of the arms diverging in right angular relation to the arms to provide oppositely extending pintles, the fingers of said base being extended over said pintles adjacent the end portion thereof, the remaining 20 end portions of the arms being formed into clothes supporting members.

2. As a new article of manufacture, a base member having opposed fingers struck there-

from, one end of each finger being integral with the base, and a supporting member, 25 consisting of a single length of material having one portion extended back upon the other portion to provide clothes supporting arms, each arm reinforcing the other, the end 30 portions of the arms diverging in right angular relation to the arms to provide oppositely extending pintles, the fingers of said base being extended over said pintles adjacent the end portions thereof, the remaining 35 end portions of the arms being bent at the end of the pintle formations to prevent longitudinal movement of the pintles on the base member, one of said ends being extended in offset relation to the pintle thereof, the extremity of said end being formed into a head 40 gear supporting member, the other end being extended beneath the arms and formed into a garment supporting member.

In testimony whereof I hereunto affix my signature.

ROBT. J. BELL.
